(57) **CLAIM**

The new, original, and ornamental design for a multiple flag holder.

DESCRIPTION

FIG. 1 is a top perspective view of a multiple flag holder showing my new design;

FIG. 2 is a top plan view of the multiple flag holder of FIG. 1;

FIG. 3 is a bottom plan view of the multiple flag holder of FIG. 1;

FIG. 4 is a front elevational view of the multiple flag holder of FIG. 1;

FIG. 5 is a rear elevational view of the multiple flag holder of FIG. 1;

FIG. 6 is a left-side elevational view of the multiple flag holder of FIG. 1; and,

FIG. 7 is a right-side elevational view of the multiple flag holder of FIG. 1.

The broken lines are shown for the purpose of illustrating both parts of the article as well as exemplary environmental subject matter. None of the broken lines form part of the claimed design.

1 Claim, 7 Drawing Sheets
